HEDDLE BAR MOUNTING

Samuel R. Floyd, Atlanta, Ga., assignor to Frank G. North, Inc., Atlanta, Ga., a corporation of Georgia

Application November 13, 1939, Serial No. 303,982

8 Claims. (Cl. 139—92)

The invention relates to a heddle bar securing device for mounting a horizontally extending flat heddle bar to a horizontally extending rail of a heddle frame in a loom construction.

The primary object of the invention is to provide a simple form of heddle rod support or lock hook which will provide for a more positive engagement with the heddle bar than is afforded by present known similar devices.

The present disclosure particularly features a form of support which will provide minimum width and maximum rod bearing surfaces and at the same time to provide such a support as will not cause excessive parting of the heddles and which will permit the passing of the heddles from one side of the support to the other, while the heddle frames are in the loom.

A still further object of the invention is to provide a form of support in the form of a clamp with wide bearing clamping surfaces for engaging the heddle bar and which will maintain firm engagement therewith even under conditions where the parts become worn in use.

Still another object of the invention is to provide a structure which will permit a ready and quick insertion and removal of the heddle bar from the support in case it is desired to replace the heddle bar in use with a different one or one of different size.

Various other objects and advantages of the invention will be in part obvious from an inspection of the accompanying drawing and in part will be more fully set forth in the following particular description of one form of device embodying the invention, and the invention also consists in certain new and novel features of construction and combination of parts herein-after set forth and claimed.

In the accompanying drawing:

Fig. 1 is a view in front elevation of a preferred embodiment of the invention shown screwed into a heddle frame rail shown in dotted outline and shown engaging and supporting a heddle bar and also showing the retaining bar in full lines in its normal clamping position and in dotted lines swung into an inoperative position;

Fig. 2 is an edge view of the device shown in Fig. 1 with the retaining bar sprung from its full line into its dotted line position; and

Fig. 3 is a vertical sectional view taken axially of the device shown in the preceding figures.

In the drawing there is represented diagrammatically a heddle frame of a loom by a horizontally extending rail A and a horizontally extending flat heddle bar B, in this particular case

having greater width considered vertically as shown in Fig. 1 than thickness considered horizontally as shown in Figs. 2 and 3.

The device 10 for supporting the heddle bar from the rail includes a main supporting member 11 comprising an upper plate 12 having a straight lower edge 13 forming the upper shoulder outlining a recess hereinafter described for receiving the heddle rod B. The plate 12 is provided mid-length with a flat pivot bearing portion 14 and thereabove with an extension 15 forming a screw by means of which the device is screwed into the rail A wherever it is desired to mount such a heddle bar support. The axis of the screw 15, prolonged downwardly, passes across the recess 18 parallel to its rear wall 19, so that after the screw is located in position, it may be rotated slightly in either direction about its own axis to bring the flat rear wall 19 parallel to the plane of the adjacent face of the heddle rod B. The main supporting member 11 also includes a plate 16 depending from the plate 12 and provided on its front side with a straight edge 17 forming a lower shoulder or supporting ledge. The space between the shoulders 13 and 17 forms a recess 18 of rectangular or rectilinear form with a flat rear wall 19. The plates 12 and 16 coact to form an element or jaw of a clamp which constitutes the lower portion of the main supporting member 11. A retaining bar 20 constituting a keeper is pivotally connected to the plate 12 at its bearing surface 14, as hereinafter described, and normally extends lengthwise of the main supporting member, and across the recess and projects for a short distance below the plate 16 to provide an extension 21 forming a finger piece for manipulating the retaining bar.

The retaining bar 20 is pivotally and resiliently mounted on pivot pin 22 provided at one end 40 with a head 23 and at the opposite end with spring washer 24 which acts through the head 22 to hold the retaining member 20 in whatever position it may be swung. The upper end of the member 20 is provided with a restraining means 45 for locking the bar 20 in its normal position as shown in full lines in the several figures. This restraining means includes a knife-like edge 25 projecting rearwardly from the upper rear face of the bar 20 and held in slot 26 formed in the bearing portion 14. With this construction it is appreciated that normally the bar 20 will be held in position against any accidental movement therefrom but is responsive to a forceful swinging movement about its pivotal support to shift the bar 20 from the full line into the dotted line

position shown in Fig. 1. The construction also permits the engagement of the finger piece 21 to move the lower portion of the bar 20 outwardly at right angles to the plane of the bar B and in the direction indicated by the arrow in Fig. 3, from the full line to the dotted line position shown in Fig. 2 so as to slip a heddle bar B into the recess by lifting the bar edgewise upwardly between the lower end of the bar 20 and plate 16 until it is received in the recess as shown in Fig. 2 after which the retaining bar is permitted to snap back under the action of the resilient washer 24 into the full line position shown in Fig. 2.

The retaining bar 20 is provided midlength with an offset portion 26 normally faces the recess 18 and in the absence of the heddle bar B intrudes more or less into the recess to engage the outer face of the heddle bar. By the use of this offset it is, of course, possible to mount in the recess heddle bars having a thickness less than the depth of the recess and at the same time hold such thin heddle bars snugly against the rear wall 19 of the recess. It is even possible to mount in the recess heddle bars having a thickness of material greater than the depth of the recess for the parts are so proportioned in the length of the shank of the pivot pin 22 and in the construction of the spring 24 to insure the bearing or clamping action herein featured even though the heddle bar projects beyond the outer face of the main support.

It is particularly noted that the heddle bar snugly fits in the recess so that there is provided a large bearing area between the rear side of the heddle bar and the support equal to the full width of the support. The shoulders 13 and 17 provide edge bearings for the heddle bar so that possibility of the heddle bar rotating about a horizontal axis is avoided. As the elements forming the jaw clamp are firmly held together by virtue of the resiliency inherent in the washer 24 and thus possibility of the heddle bar being jolted out of its support is avoided, at the same time a structure is provided which will permit the ready installation and displacement of the heddle bars in place either by swinging the bar 20 about its axis to clear the recess as indicated by the dotted line showing in Fig. 1 or by springing the bar 20 forwardly as shown by the arrow in Fig. 3, both operations being effected by simple manual operation and without necessity of using tools to demount the holding parts.

While there have been shown, described and pointed out in the annexed claims, certain novel features of the invention, it will be understood that various omissions, substitutions and changes in the form and details of the device illustrated and in its operation may be made by those skilled in the art without departing from the spirit of the invention.

I claim:

1. The combination with a heddle frame comprising a horizontally extending rail and a horizontally extending flat heddle bar having greater width considered vertically than thickness considered horizontally, a heddle bar securing device including a flat plate extending in the plane of the heddle bar, having a screw at one end engaging in the rail and provided on one side with a wide recess in which the heddle bar is fitted flatwise to provide a wide flat bearing between the bottom of the recess and the adjacent flat side of the heddle bar, and a retaining bar constituting a keeper carried by the plate in flatwise engage-

ment with the opposite side of the heddle bar and means for resiliently mounting the retaining bar, and said retaining bar acting resiliently in a direction transversely of the flat sides of the heddle bar to clamp the heddle bar snugly between the two broad faces provided by the bottom of the recess and by the flexible retaining bar.

2. The combination with a flat heddle bar, of a support therefor including a clamp, one element of which is provided with a recess in which a mid-portion of the bar snugly fits and the other element of which is pivotally connected to the first named element and is provided with an offset bearing portion located to intrude into the recess in the absence of the heddle bar and acting to engage the heddle bar and hold it in clamped position in the recess, said other element being pivoted to the first named element to swing in the plane of the heddle bar into an inoperative position to expose the recess and said other element being resiliently mounted so as to permit it to be sprung at right angles to said plane and away from the heddle bar to permit the withdrawal and replacement of the heddle bar without rotating said other element.

3. A heddle bar securing device provided with screw means for mounting it in place on a heddle frame and comprising a support adapted to extend flatwise in the plane of the heddle bar and provided on one of its flat sides with a recess for receiving the heddle bar in flatwise engagement with the support, a retaining bar pivotally connected to the support for engaging the heddle bar to secure the same in the recess, and movable in the plane of the heddle bar, pivotal mounting means between the retaining bar and the support said mounting means including a spring tending to resist accidental movement of the retaining bar out of its operative position.

4. A heddle bar support comprising a main supporting member having an extension in the form of a screw, said member provided on one side thereof with a recess of rectilinear form with its rear wall flat and having the width of the heddle bar which it is designed to contact, a retaining bar, a spring pressed pivot pin for pivotally and resiliently connecting the bar to the main support and said bar having a portion overlapping the recess for bearing on and thus clamping the heddle bar against said rear wall.

5. A heddle bar support comprising a main supporting member having means for mounting it in place on a heddle frame, said member having a flat side with a recess of rectilinear form adapted to receive the heddle bar therein, a retaining member carried by the main member and having an offset portion intruding into the recess and resilient means reacting between said members to cause the offset portion of the retaining member to bear on one flat side of whatever heddle bar may be located for the time being in the recess.

6. A heddle bar securing device including a support having a recess in one side thereof having at least the width and depth of the heddle bar which it is intended to secure and having a retaining member carried by the support and having means for engaging the exposed side of the heddle bar when mounted in the recess to maintain the heddle bar snugly in its position in the recess, and resilient means distinct from and acting on the retaining member to maintain the same in continuous flatwise bearing engagement with the heddle bar as the support, heddle bar and retaining member become worn in use.

7. A heddle bar support provided with means

for mounting it in place on a heddle frame and including a main supporting member provided on one side with a flat rectangular shaped recess adapted to have a portion of a heddle bar fitted therein in flatwise engagement with the rear wall of the recess, and a retaining member overlapping the recess and provided with an offset portion facing the recess for engaging the heddle bar and bearing on the same for forcing the same snugly against said rear wall even though the heddle bar may be of less thickness than the depth of the recess.

8. A heddle bar mounting comprising a main supporting member provided midlength thereof with a pivot bearing portion, one end of said member forming a screw extension and the other

end forming a jaw of a clamp and provided on one of its flat faces with a recess having a flat rear wall adapted to receive therein a heddle bar in flatwise engagement with said flat rear wall, 5 a retaining bar extending flatwise parallel to the plane of the flat rear wall of the recess and extending across the recess and constituting the coacting jaw of the clamp, a pivot pin passing through the retaining bar adjacent one end and through the bearing portion and a spring washer reacting between the pin and bearing portion tending to hold the retaining member in whatever position it may be swung and acting in a tendency to cause the jaws to approach each other when in their operative clutching position.
